UNITED STATES PATENT OFFICE.

GEORGE M. HARSH, OF BALTIMORE, MARYLAND, ASSIGNOR TO FAULTLESS NIGHT-WEAR CORPORATION, A CORPORATION OF MARYLAND.

GARMENT.

Application filed December 13, 1922. Serial No. 606,616.

To all whom it may concern:

Be it known that I, GEORGE M. HARSH, a citizen of the United States of America, residing in the city of Baltimore, State of Maryland, have invented certain new and useful Improvements in Garments, of which the following is a specification.

The invention relates to a garment of the shirt or coat type particularly adapted for use as the upper or coat portion of a pajama suit. One of the principal difficulties encountered in the use of such garments is that incident to the fastening of the garment at the front. Ordinarily buttons have been used. These are objectionable both on account of the frequency with which they are pulled off when being washed and in use and because of inconvenience and discomfort on account of cutting and scratching of the wearer's skin by the buttons.

Buttonless garments have been attempted but it has been found necessary to cut these so low in the neck as to involve danger and discomfort on account of exposure of the pulmonary region. The present garment is buttonless but it is so arranged at the neck as to give sufficient opening to pass the head without carrying this opening so low as to unduly expose the chest.

The garment as disclosed also has great advantages as to economy of material and labor required in producing it. Economy in the production of the garment of the invention in the preferred form results from the design of the garment which is constructed in such a way that it is possible and feasible to make the entire body portion from a single piece of material which is folded transversely over the shoulders to form the front and back, the edges of the material being sewed together at the sides. The garment is preferably made with a tapering plait on each shoulder which gives the desired fit at this point without cutting of the material. This plait also has a certain reinforcing effect similar to that of a yoke.

In the drawing Figure 1 is a front elevation;

Figure 2 is a side elevation of the garment on a reduced scale, the sleeves being removed for convenience of illustration;

Figure 3 is a plan of the shoulder portion of the garment or more particularly the material cut in the form of the garment

and spread out flat, the front and back ends of the material being removed;

Figure 4 is a fragmentary view illustrating the shoulder plait.

Referring to the drawings by numerals 60 the garment as illustrated consists of a body portion 1 which may, if desired, be provided with sleeves 2 of any preferred length. As shown these sleeves are of only one-quarter length and it is believed that this type of sleeve is preferable for this garment. The material is ordinary flat goods meaning that it is woven as distinguished from knit goods.

The body portion 1 is made of a single 70 piece of material of twice the length of the body of the garment. To shape the material in accordance with the pattern, a piece of suitable width equal to half the circumference of the garment around the waist or 75 whatever may be the widest portion is cut to a little over twice the length of the garment. Centrally of this a hole is cut for the neck, the same being preferably sharply tapered toward the front and back. This hole is a little forward of the longitudinal center so that while the back is cut slightly low it is not as low as the front and the circumference of the opening which is long, narrow and tapered at the ends as shown, 80 85 is sufficient to pass the head.

The long tapered neck opening as best 90 shown in Figure 3 is an important feature of the invention whereby a buttonless garment is made feasible for this purpose as it gives sufficient length of the edges to pass the head without a sufficient area of opening to give objectionable or dangerous exposure. The back portion of the neck is indicated by reference character 3 and the 95 front by reference character 4. The neck opening may, if desired, be bound by sewing to the edges thereof a suitable strip of material 5.

The shoulders are formed by folding the 100 material at each side of the center of the neck opening as indicated and sewing it in two plaits, preferably of increasing width outwardly from the neck portion toward the edges. The plaits thus tapered serve as 105 a reinforce taking the place of a yoke and give the necessary incline to the shoulders resulting in the desired fit as illustrated.

The arm holes are cut in an obvious manner being formed by curves 7 and 8 in the 110

opposite edges of the material at the ends of the shoulder plaits. The material as cut is next folded over about the plaited portion and the meeting edges below the arm holes are sewed together forming the body of the garment. A pocket 9 may be added if desired.

Sleeves are not essential to the garment structure but they may be provided of three-quarters length or any preferred length as indicated by reference character 2, being sewed into the arm holes in an obvious and well known manner.

Important features of the invention are first the elongated tapered neck portion as shown which gives sufficient length to the edges of the opening to pass the head, at the same time keeping the neck of the garment as worn sufficiently closed to prevent undue exposure, and the one piece structure, the body portion of which is formed by folding the length of material about the transverse line of the shoulders and fitting by providing a preferably tapered plait of the top of the shoulders.

I have thus described specifically and in detail a garment constructed in accordance with the preferred form of the invention in order that the nature and operation of the

same may be clearly understood, however, the specific terms herein are used descriptively rather than in a limiting sense, the scope of the invention being defined in the claim.

What I claim and desire to secure by Letters Patent is:

A buttonless pajama coat, the body portion of which is formed in a single piece consisting of a strip of woven inelastic material of a width equal to half the circumference of the garment, the said strip having a neck opening centrally located and elongated in the direction of the length of the strip, plaits of outwardly increasing width extending from near the center of the neck portion to the outer edges of the strip on each side, the meeting edges of the material being secured together from the bottom to a point below the shoulder, the upper portions at the ends of the plaits being left open to form the arm holes.

Signed by me at Baltimore, Maryland, this 11th day of December, 1922.

GEORGE M. HARSH.
